[57] CLAIM

The ornamental design for a banking machine terminal, as shown and described.

DESCRIPTION

FIG. 1 is a front perspective view of a banking machine terminal showing my design;

FIG. 2 is a front elevation thereof;

FIG. 3 is a top plan view thereof;

FIG. 4 is a left-side elevation view; and

FIG. 5 is a right-side elevation view.

The back is plain and unornamented.

FIG. 1
